UNITED STATES PATENT OFFICE.

EUGÈNE SCHNEIDER, OF LE CREUZOT, FRANCE.

BREECH MECHANISM OF GUNS.

1,076,842.

Specification of Letters Patent. Patented Oct. 28, 1913.

Application filed November 27, 1911. Serial No. 662,657.

To all whom it may concern:

Be it known that I, EUGÈNE SCHNEIDER, a citizen of the Republic of France, and a resident of Le Creuzot, Saône-et-Loire, France, have invented a new and useful Improvement in or Relating to the Breech Mechanism of Guns, which is fully set forth in the following specification.

This invention relates to the breech mechanism of guns and has for its chief object to reduce to a minimum the friction of the breech screw in the threads of the breech chamber during the greater part of the screwing and unscrewing of the breech, thereby eliminating wear and permitting the breech to be readily opened even in the case of binding between the threads of the breech screw and of the breech chamber, the arrangement being such as to insure intimate contact between the breech screw and the threads of the breech chamber when the breech is closed.

According to this invention the threads of the breech screw instead of being so formed as to fit those of the breech chamber exactly, are formed in such a manner that when the breech is closed they bear with their rear faces against the front faces of the threads of the breech chamber, suitable play being reserved between the other face of the screw threads and the corresponding faces of the threads of the breech chamber. The breech screw instead of being engaged directly with its support, that is to say with the carrier, engages with a nut or with an externally screw threaded collar (the pitch of which is shorter than that of the breech screw) capable of moving longitudinally with respect to the carrier, the said nut or collar being retained against a part of the carrier by a spring which is given a suitable initial tension.

It follows that the breech screw, which a short time after the beginning of the unlocking operation, when the longitudinal movement of the nut or collar has ceased, takes a slower movement in the breech chamber owing to the shorter pitch of said nut or collar and has thus acquired complete freedom in the latter, is able, during the whole of the rest of the unlocking movement to recede on or in the supporting nut or collar while at the same time rotating freely (without any friction) in the breech chamber.

Inversely for closing, the breech screw

first of all occupies in the breech chamber the free position that it has at the end of the unlocking movement and the locking movement then produces an advance of the breech screw upon or in the supporting nut or collar; this movement being somewhat smaller delays the displacement in the screw chamber. A short time before the end of the locking movement, the rear faces of the threads of the breech screw bear upon the front faces of the threads of the breech chamber which displace the screw carrying with it the supporting nut and compressing the counter spring. The friction of the breech screw in the breech chamber does not occur except during a very small part of the travel.

In order that the said invention may be more clearly understood and readily carried into effect I will describe the same more fully with reference to the accompanying drawings, in which:

Figures 1 and 2 illustrate one constructional form of the invention in longitudinal section, Fig. 1 showing the position of the parts when the breech is completely closed and Fig. 2 the parts when the breech screw is unlocked before the complete opening by the angular displacement of the carrier about its hinge pin. Figs. 3, 4 and 5 show in partial longitudinal section the respective positions of the threads of the screw and of the threads of the breech chamber in the various phases of the movement of unlocking and of locking the breech screw. Figs. 6 and 7 show in longitudinal section a second constructional form of the invention the breech screw being in the locked and unlocked position respectively. Figs. 8 and 9 illustrate a third construction in the same two positions and in longitudinal section.

In these various figures *a* designates a breech screw of any known type and *b* the breech of the gun.

The threads of the breech screw *a* are cut in such a manner that when the breech is completely closed (Figs. 1, 3, 6 and 8) their rear face *a'* bears against the front face *b'* of the threads of the breech chamber, a suitable amount of play *x* being reserved between the front faces *a*² of the threads of the breech screw and the rear faces *b*² of the threads of the nut; this is clearly shown in Fig. 3. The breech screw *a* instead of being engaged directly in screw threads in the carrier *e* is engaged by means of

threads *c* in or upon a supporting nut or collar *d*. This nut or collar *d* is capable of longitudinal displacement in the carrier *e*; with this object it can slide for example on 5 a key or feather *f* engaging in a keyway in the carrier to prevent the said nut or collar from rotating in the latter. A powerful spring *g* bearing upon the carrier and upon the nut or collar *d* constantly tends 10 to prevent any longitudinal displacement of the nut or collar in the forward direction; when the nut or collar *d* has encountered the carrier *e* it can no longer move forward as it is locked by the said spring. The initial tension of the spring is such that any 15 accidental movement of the breech screw *a* in the carrier *e* is prevented whatever the angle of elevation of the gun may be.

In the examples illustrated in Figs. 1, 2 20 and 6, 7 the pitch of the screw threads *c* is smaller than that of the threads of the breech screw *a* and of the breech chamber. In the first example of the invention (Figs. 1 and 2) the screw threads 25 *c* are formed on the stem *a*² of the breech screw. In this example the supporting nut *d* is arranged in a recess in the boss of the carrier *e* and guided on a key *f* keyed in this boss. The spring *g* bears against 30 the front face of the supporting nut *d* and upon a plug *h* screwed into the boss of the carrier.

When the breech is completely closed the parts occupy the position shown in Figs. 1 35 and 3. The faces *a'* of the threads of the breech screw bear against the faces *b'* of the threads of the breech chamber the clearance *x* being left between the faces *a*² and *b*². A clearance *y* exists between the rear face 40 of the supporting nut *d* and the bottom of the recess in the carrier *e*.

When the breech screw *a* is first of all actuated with the object of opening the breech, it is driven during about 1/16th of the unscrewing operation, by the breech chamber; at the same time, however, the threads *c* owing to their shorter pitch rotate in the supporting nut *d* in such a manner that the latter is displaced longitudinally in its 45 recess (owing to the difference in pitch of the threads of the breech screw and the nut) until it has receded by the amount *y*. From this moment as the supporting nut *d* is unable to recede farther, it begins by means of 50 the threads *c* to displace the breech screw *a*, and as the pitch of the threads *c* is smaller than that of the threads *a'* *a*² the latter leave their support upon the nut *b*, assume the position shown in Fig. 4 and then rotate 55 freely. 15/16ths of the unscrewing thus take place during the displacement of the threads *c* in the supporting nut *d*, the threads of the breech screw rotating freely and not experiencing any wear. Fig. 2 60 shows the position of the various parts at

the end of the unlocking movement of the breech screw. Fig. 5 shows the relative position of the threads of the screw and those of the breech chamber at this moment.

It will be observed that during the greater part (15/16ths of the rotation for example) of the unscrewing movement the friction is limited to that of the threads *c* in the supporting nut, which amount of friction is negligible in comparison with that which would otherwise be produced between the breech screw *a* and the breech chamber. By reason of the wear of the breech screw and of its chamber being reduced to the minimum, the operations of opening and closing 70 can always be effected with the greatest ease. 75

When it is desired to close the breech the parts occupy the position shown in Figs. 2 and 5 before the locking operation is started. At the commencement of the rotation the breech screw *a* rotates freely in the nut *b*; and it is displaced by the displacement of the threads *c* in the supporting nut *d*. When 15/16ths of the rotary locking movement have been effected the threads of the screw *a* owing to the fact that their pitch is greater than the pitch of the threads *c*, have experienced a retardation in the forward movement in such a manner that the faces *a'* and *b'* come into contact (Fig. 3). From 80 this moment the screw breech *a* is displaced more rapidly in the breech chamber and the supporting nut *d* is displaced longitudinally in compressing the spring *g* and finally regaining the play *y* in its recess when the 85 locking movement is completed. 90

As in the unlocking operation, friction between the threads of the breech screw and chamber exists only during 1/16th part 95 of the locking operation. 100

If binding should accidentally occur after 105 firing the prompt opening of the breech can always be insured, as it is only necessary in such cases to exert a forward thrust directly upon the breech screw *a* (by suitable means such for example as a jack) in such a manner as to detach the faces *a'* from the faces *b'* (this being possible owing to the clearance *x*) and to rotate the screw rather more than 1/16th of a revolution. 110 From this moment the threads *a'* *a*², having 115 lost all contact with the threads of the breech chamber, occupy the position shown in Fig. 4 and the opening can be completed normally. 120

In the example illustrated in Figs. 6 and 7 the screw threads *c* of reduced pitch are formed in a recess in the breech screw *a*; the supporting collar *d* is guided upon the boss *e'* of the carrier *e* and is prevented 125 from rotating by a key *f* in this boss. The spring *g* bears upon the collar *d* and upon a plug *h* screwed on the said boss *e'*.

The operation is exactly the same as in the preceding example. 130

In the example illustrated in Figs. 8 and 9 the screw threads *c* engage without play in the supporting nut *d*, (which is guided in the carrier *e*) and are provided on the outside of the screw *a* itself so as to constitute a simple extension of the thread *a'* *a*². The supporting nut *d* carries a collar *d'* for the reception of which a corresponding recess is formed in the carrier *e* and which is able to bear against the bottom *e'* of this recess. The nut *d* is formed in two parts *d* *d*² the part *d*² being screwed upon the other and forming a support for the spring so that the initial tension of the latter can be regulated.

The depth of the supporting nut *d* is slightly less than that of the carrier *e* so that when the latter in closing has taken a bearing upon the rear face of the gun while the breech screw *a* has taken a bearing upon the carrier by means of its collar *a'*, the said nut *d* can move rearward.

Fig. 8 shows the parts in the position that they occupy when the breech is completely closed. The clearance *x* exists between the front faces *a*² of the threads of the breech screw *a* and the rear faces *b*² of the threads of the breech chamber. Clearance also exists between the front of the nut *d* and the rear face of the gun in the same way that clearance *y* exists between the collar *d'* and its bearing face *e'*.

At the commencement of the unlocking operation the breech screw *a* loses contact with its chamber *b* and rotates freely in same permitting of the longitudinal displacement of the supporting nut *d* which is prevented from rotating. As soon as the nut has traversed the clearance *y* under the influence of its spring *g* which clearance corresponds to say 1/16th of the unscrewing movement of the breech screw it bears by means of its collar *d'* upon the face *e'* of the carrier. The breech screw *a* continuing to rotate in the nut *d* which then is steady and the threads *a'* *a*² being still out of contact with the threads of the breech chamber, the unscrewing is entirely effected with the parts in contact only with the nut *d*, the rotation taking place freely in the breech chamber.

At the end of the unlocking operation the parts assume the position shown in Fig. 9. The reverse action takes place when the breech is being closed. The parts start with the position shown in Fig. 9 and during the entire locking operation the rotation of the breech screw is free in the breech chamber. When in its entering movement the breech screw bears by means of its collar *a'* upon the carrier *e* it is prevented from advancing. In continuing to rotate in position it draws the supporting nut *d* rearward and compresses the spring *g*. The faces *a'* of the screw threads again bear upon the faces *b'*

of the threads in the breech chamber and the play *y* is re-established between the collar *d'* and its bearing face *e'*. To readily open the breech in case of binding, the collar *a'* which would be screwed on the breech screw, would be unscrewed in order to exert pressure on the breech screw.

What I claim and desire to secure by Letters Patent of the United States is:—

1. In a gun, the combination of a breech provided with screw-threads and a breech screw provided with corresponding screw-threads, a clearance being provided between half of the contiguous and homologous faces of said threads whereby said breech screw may have a slight longitudinal movement imparted thereto when the breech is completely closed. 75

2. In a gun, the combination of a breech provided with screw-threads, and a breech screw provided with corresponding screw-threads, a clearance being provided between the front faces of the threads on one of said parts and the rear faces of the threads on the other of said parts when the breech is 85 completely closed.

3. In a gun, the combination of a breech provided with screw-threads, and a breech screw provided with corresponding screw-threads, a clearance being provided between 90 the front faces of the threads on the breech screw and the rear faces of the threads in the breech when the breech is completely closed.

4. In a gun, the combination of a breech provided with screw-threads and a breech-screw provided with corresponding screw-threads, a clearance being provided between half of the contiguous and homologous faces of said threads when said breech-screw 105 is screwed home in the breech.

5. In a gun, the combination of a breech provided with screw-threads and a breech-screw provided with corresponding screw-threads concentric with the axis of said 110 breech-screw, a clearance being provided between half of the contiguous and homologous faces of said threads when said breech-screw is screwed home in the breech.

6. In a gun, the combination of a breech provided with screw-threads, and a breech-screw provided with corresponding screw-threads concentric with the axis of said breech-screw, a clearance being provided between the front faces of the threads on one of 120 said parts and the rear faces of the threads on the other of said parts when the breech is closed.

7. In a gun, the combination of a breech provided with screw-threads, and a breech-screw provided with corresponding screw-threads concentric with the axis of said breech-screw, a clearance being provided between the front faces of the threads on the breech-screw and the rear faces of the 130

threads in the breech when the breech is closed.

8. In a gun, the combination of a breech, a carrier pivoted adjacent said breech, a breech block engaging in the breech and provided with screw-threads, a member movable relatively to said carrier during the unlocking of said breech block, said member being provided with screw-threads engaging those on said breech block and being movable relatively thereto.

9. In a gun, the combination of a breech, a carrier pivoted adjacent said breech, a breech block engaging in the breech and provided with screw-threads, a member movable relatively to said carrier during the unlocking of said breech block, said member being provided with screw-threads engaging those on said breech block.

10. In a gun, the combination of a breech, a carrier pivoted adjacent said breech, a member movable longitudinally of the carrier and provided with screw-threads, and a breech block mounted on said carrier and engaging in the breech and provided with screw threads engaging those on said member.

11. In a gun, the combination of a breech, a carrier pivoted adjacent said breech, a spring-pressed member having a limited movement longitudinally of said carrier and provided with screw-threads, and a breech block mounted on said carrier and engaging in the breech and provided with screw-threads engaging those on said member.

12. In a gun, the combination of a breech, a carrier, a spring-pressed member having a limited movement longitudinally of said carrier and provided with screw-threads, means for preventing rotation of said member, and a breech-block mounted on said carrier engaging in the breech and provided with screw-threads engaging those on said member, said block being rotatable on said member.

13. In a gun, the combination of a breech, a carrier pivoted adjacent said breech, a member mounted on the carrier and movable longitudinally with respect thereto, a breech block mounted on said carrier and engaging in the breech, and connections between said member and breech block whereby the latter is rotatable on the former.

14. In a gun, the combination of a breech provided with screw-threads, a carrier piv-

oted adjacent said breech, a member provided with screw-threads mounted on said carrier and movable longitudinally with respect thereto, a breech block mounted on said carrier and provided with two sets of screw-threads, one set engaging those in the breech and the other set those on said member.

15. In a gun, the combination of a breech provided with screw-threads, a carrier, a member provided with screw-threads of a smaller pitch than those in the breech mounted on said carrier and movable longitudinally with respect thereto, a breech block mounted on said carrier and provided with two sets of screw-threads one set engaging those in the breech and the other set those on said member.

16. In a gun, the combination of a breech provided with screw-threads, a carrier, a spring-pressed member mounted on said carrier provided with screw threads and movable longitudinally with respect to said carrier, and a breech block mounted on said carrier and provided with two sets of screw-threads one set engaging those in the breech and the other set those on said member.

17. In a gun, the combination of a breech provided with screw-threads, a carrier, a spring-pressed member mounted on said carrier provided with screw-threads of a smaller pitch than those in the breech and movable longitudinally with respect to said carrier, and a breech block mounted on said carrier and provided with two sets of screw-threads one set engaging those in the breech and the other set those on said member.

18. In a gun, the combination of a breech provided with screw-threads, a carrier, a spring-pressed member mounted on said carrier provided with screw-threads of a smaller pitch than those in the breech and movable longitudinally with respect to said carrier, means for preventing said member from rotating on said carrier, and a breech block mounted on said carrier and provided with two sets of screw-threads one set engaging those in the breech and the other set those on said member.

In testimony whereof I have signed this specification in the presence of two subscribing witnesses.
